NONREFILLABLE BOTTLE

Ludwig A. Ihlein, Philadelphia, Pa.

Application September 26, 1935, Serial No. 42,259

7 Claims. (Cl. 215—14)

The object of my invention is to devise a novel construction and arrangement of a nonrefillable bottle wherein when the nonrefillable feature is locked it cannot be reopened without breaking the bottle.

With the above and other objects in view as will hereinafter clearly appear, my invention comprehends a novel nonrefillable bottle.

It further comprehends a novel nonrefillable bottle having a vent passage and a movable closure and novel means for positively closing the vent passage and at the same time retaining the closure in its closed position.

Other novel features of construction and advantage will hereinafter more clearly appear in the detailed description and the appended claims.

For the purpose of illustrating the invention, I have shown in the accompanying drawings typical embodiments of it, which in practice, will give satisfactory and reliable results. It is, however to be understood that the various instrumentalities of which my invention consists can be variously arranged and organized, and my invention is not limited to the exact arrangement and organization of these instrumentalities as herein set forth.

Figure 1 is a front elevation partly in section of a bottle and nonrefillable mechanism, embodying my invention.

Figure 2 is a sectional elevation on an enlarged scale.

Figure 3 is a sectional elevation of a portion of the mechanism.

Figure 4 is an exploded view of a valve, valve cage and valve.

Figure 5 is a section on line 5—5 of Figure 2.

Figure 6 is a top plan view of the bottle and its adjuncts.

Figure 7 is a fragmentary inverted view, in section, showing more clearly the relation of the parts when a liquid is being poured from the bottle.

Figure 8 is a sectional elevation of another embodiment of my invention.

Figure 9 is a sectional view of the device in pouring position.

Figure 10 is a section on line 10—10 of Figure 8.

Figure 11 is a section taken on the same line as Figure 10 but showing the parts in locked position.

Figure 12 is a top plan view of Figure 8.

Figure 13 is a section on line 13—13 of Figure 8.

Figure 14 is a section on line 14—14 of Figure 8.

Figure 15 is a section on line 15—15 of Figure 8.

Figure 16 is a section on line 16—16 of Figure 8.

Figure 17 is a detail of certain parts of the locking mechanism in unlocked position.

Figure 18 is a view similar to Figure 17, but showing the parts in locked position with the vent passage sealed.

Figure 19 is a detail of means employed for venting the rotation of the closure in more than one direction.

Figure 20 is a view similar to Figure 19 but showing the parts in different relation from that seen in Figure 19.

Referring first to the embodiment seen in Figures 1 to 7, inclusive, 1 designates a bottle having any desired contour and provided with a neck 2 to receive the nonrefillable mechanism. The body portion of the nonrefillable mechanism is in the form of a casting 3 closed at its top and bottom except for an inlet opening 4 in the bottom and a discharge opening 5 in the top. The casting 3 may be fixed in the neck of the bottle in any desired or conventional manner. By way of illustration, I have shown an outer sleeve 6 cemented or otherwise secured in the neck and an inner sleeve 7, the sleeves having interlocking members formed by tapered projecting portions 8 on one member in correspondingly shaped recesses 9 on the other member.

The casing 3 may be cemented, soldered or spot welded to the inner sleeve 7.

The inlet 4 has its marginal wall upwardly deflected to receive the lower end of a flexible tubular valve 10 cemented or otherwise secured thereto. This valve 10 is preferably of rubber, has its discharge end flattened and has its inlet end adapted to receive a ball valve 11 to seal it. The ball valve 11 is in a skeleton cage 12 carried by the bottom of the casing 3, and the ball cage is of less diameter intermediate its ends so that the ball valve will be normally retained in the lower portion of the cage, so that the liquid can pass freely to and through the valve 11.

13 is a vent passage, open at its upper end, and having a flexible tube 14 connected with its lower end and passing through the cage above the ball valve. The closure 15 has limited relative movement with the top of the casing 3 due to the prongs 16 which extend beneath the top. A sleeve 17 is secured to the closure 15 to receive a cord 18 fastened at one end to the closure. This cord 18 passes through the valve 10 and has its lower end fixed to the ball valve 11.

Any desired baffling arrangement may be used to prevent insertion of a wire or other tool to unseat the ball valve when the latter is seated in the valve 10. A lower baffle 19 has a general

conical contour with side discharge openings 20 and members 21. 22 is an intermediate baffle with side discharge openings 23. 24 is an upper annular baffle with a central discharge opening 25. 5 In the operation of this embodiment of my invention, when the parts are in the position seen in Figures 1 and 7, the liquid will pour from the bottle when the latter is inverted as seen in Figure 7.

10 The vent passage 13 at its upper end is provided with a check valve 26 of any conventional construction which is closed when the bottle is in upright position and which is open when the bottle is inverted for pouring.

15 When the bottle is empty, the operator turns the closure 15, thereby twisting the cord 18, and raising the ball valve by the restricted intermediate portion which normally prevents the ball valve passing outwardly.

20 The force of the pull on the cord draws the ball valve by the restricted portion of the cage into the valve 11 sealing its discharge opening as seen in Figure 3. At the same time it closes the flexible tube 14, thereby closing and sealing the 25 vent passage and preventing the refilling of the bottle by suction and pressure. At the same time the closure 15 is drawn tightly against the top of the casing 3.

As the ball valve 11 cannot now be unseated 30 due to its frictional grip on the flexible walls of the recess of the valve 11, the bottle cannot be refilled unless the neck of the bottle is broken off, thereby destroying the bottle for further use.

35 The conventional cap sleeve for sealing the closure 15 and the discharge opening 5 is employed when the bottle is shipped from the place where it has been filled, and removed when the bottle is to be used.

40 The embodiment seen in the other figures of the drawing is a preferred form as it is simpler and cheaper to manufacture.

45 Referring now to the embodiment seen in Figures 8 to 20 inclusive, I have shown in these figures a preferred and simplified embodiment of my invention, wherein novel means are employed to positively seal the vent passage.

50 The casing 27 is similar to that in Figure 1, having a bottom with an inlet opening 28 and a top with a discharge opening 29. The inlet opening leads to a tubular flexible valve 30, preferably of rubber. In order to form a circuitous passage from the valve to the discharge opening 29, baffles are employed. The lower conical baffle 31 surrounds the valve and has its discharge opening directed laterally. The intermediate baffles 32 are in different planes forming a discharge opening 33, beneath the upper baffle 34 which has openings 35 near its periphery.

55 An abutment 36 is spaced from the top face of the baffle 34 which is flat and has at its bottom an inclined face 37 which merges into a flat bottom face 38. A vent pipe 39 extends from the upper baffle a desired distance below the casing and has at its upper end a check valve 40 similar to that shown in Figure 1. 41 is a closure for the discharge port 29 and has a raised rib 42 for grasping it. The closure 41 has L-shaped pins 43 which provide for relative movement between the closure and the top of the casing. The closure 41 has a right angle arm 44 depending from it and the free end forms a valve 45 having its top leading face tapered or inclined as at 46. The pins 43 of the closure 41 cooperate with springs 47 to permit rotation of the closure in one direction only. The top of the casing has

stops 48 with which cooperate stops 49 on two of the pins 43. These same pins have springs 50 which engage opposite sides of the stops 48.

5 The operation of the embodiment seen in Figures 8 to 20 inclusive is as follows. When the bottle is inverted as in Figure 9 the liquid will cause the valve 30 to open and the valve of check valve 40 will drop downwardly opening the vent passage 39. The closure 41 will move downwardly and the liquid will pour freely from the bottle in the direction of the arrows seen in Figure 9.

When the bottle is empty and it is desired to seal it, the closure 41 is turned, the springs 50 preventing any accidental rotation of the closure.

As soon as the springs pass by the stationary 15 stops 48 the closure can be given a one half turn. The springs 41 prevent the rearward rotation of the closure. The turning of the closure wedges the valve 45 beneath the abutment 36 and closes the vent passage 39. At the same time, it draws the closure 41 into firm engagement with the top of the casing to close the discharge port 29. As the closure cannot now be turned in a rearward direction, there is no way of filling the bottle 20 without breaking it. 25

In both forms of my invention as herein shown the vent is positively closed so that the bottle cannot be refilled by a suction and pressure method.

The casing can be cemented to the bottle or to 30 a locking sleeve as in Figure 1.

Having thus described my invention, what I claim as new and desire to secure by Letters Patent is:

1. A nonrefillable bottle mechanism having a valve controlled inlet, a closure controlled discharge and a vent passage, means actuated by the turning of the closure to close said vent and move the closure to seal said discharge, and means to prevent turning of the closure in a reversed direction when in sealing position. 40

2. In a nonrefillable bottle mechanism, a casing to be secured in the neck of the bottle and having an inlet port and a discharge opening, a closure for the discharge opening having limited relative movement with the casing, a self opening 45 valve for the inlet port, said casing having a vent passage, means actuated by the turning of the closure in one direction to seal said vent passage, and seal the closure with the casing to close the discharge opening, and means to prevent the 50 turning of said closure in a reverse direction.

3. A nonrefillable bottle mechanism comprising a casing to be fixed in a bottle neck and having an inlet and a discharge opening, and a vent passage, a self closing valve for the inlet opening, a 55 closure for the discharge opening having relative movement therewith, baffles forming a circuitous passage between the inlet and discharge opening, a valve carried by the closure to seal the vent passage, and stop members to permit 60 the turning of the closure in one direction only.

4. In a nonrefillable bottle mechanism, a casing to be secured in the neck of a bottle and having an inlet and a discharge opening, a self closing valve for said inlet opening when the bottle is 65 inverted, baffles between said valve and the discharge opening, said casing having a vent passage opening through one of said baffles, an abutment, a closure for the discharge opening having limited relative movement therewith, and a valve 70 carried by the closure and forced between said abutment and the baffle on the turning of the closure to seal the vent passage and to seal the closure with the casing.

5. In a nonrefillable bottle mechanism, a cas- 75

- ing to be secured in a bottle neck and having an inlet and a discharge opening, a self closing valve for the inlet opening, superimposed baffles between the inlet and discharge openings, said casing having a vent opening through the top baffle, a closure for the discharge opening having members extending beneath the casing top, pins carried by the casing top engaging said members to prevent rotation of the closure in one direction, a valve carried by the closure and cam means to move the closure to close the discharge opening on rotation of the closure and to move the valve to close the vent.
6. In a nonrefillable bottle mechanism, a casing having an inlet and a discharge opening, baffles between said openings having staggered openings, said casing having a vent passage, a closure for the discharge opening, a valve carried by the closure to seal the vent on the rotation of the carrier, stops on the casing top, means
- 5

carried by said closure to engage said stops and permit only a partial revolution of said closure, and means to prevent accidental turning of said closure on the casing.

7. In a nonrefillable bottle mechanism, a casing having an inlet and a discharge opening, a self closing flexible valve for said inlet opening, a valve cage restricted intermediate its ends, a valve in said cage, a closure for said discharge opening, said casing having a vent passage with a compressible portion in the path of said valve in the cage, and a contractile connection between the valve in the cage and the closure and contractile on the turning of the closure to move the valve in the cage into the self closing valve 15 to seal the latter and at the same time compressing said compressible portion to seal the vent passage.

LUDWIG A. IHLEIN.
